UNITED STATES PATENT OFFICE.

WILLIAM BEARDSLEY, OF BEACON, IOWA.

BOTTLE-STOPPER.

SPECIFICATION forming part of Letters Patent No. 365,961, dated July 5, 1887.

Application filed April 4, 1887. Serial No. 233,596. (No model.)

To all whom it may concern:

Be it known that I, WILLIAM BEARDSLEY, of Beacon, in the county of Mahaska and State of Iowa, have invented a new and Improved 5 Bottle-Stopper, of which the following is a full, clear, and exact description.

This invention relates to an improvement upon that class of bottle-stoppers of which an example is given in Letters Patent No. 317,705, 10 granted to me on the 12th day of May, 1885, the object of the present invention being to dispense with the retaining-cap shown in the Letters Patent above referred to, and at the same time to provide a stopper which shall 15 be so constructed and arranged as to be self-adjusting, and one which, after the bottle has once been closed, will not be liable to become accidentally displaced so as to open the bottle.

Reference is to be had to the accompanying 20 drawings, forming a part of this specification, in which similar figures of reference indicate corresponding parts in both the views.

Figure 1 is a view in central vertical section of a bottle provided with my improved 25 form of stopper, the parts being represented as they appear when the bottle is open and empty; and Fig. 2 is a similar view representing the bottle, however, as it appears when filled and the stopper as in place against its 30 packing-ring.

In constructing such a stopper as the one illustrated in the drawings above referred to, I provide a bottle, 10, in the head of which there is formed an annular recess, 11, the 35 lower portion of said recess being of greater diameter than the upper portion thereof, so that the annular defining-walls of the recess are inclined, as shown at 2. Within the recess 11, I fit a ring, 12, that is made of flexible packing material, and preferably of rubber, the walls defining the bore of the ring and the outer peripheral face of said ring being vertical or parallel to the axis of the bottle. Prior to the introduction of the ring I 40 pass a stopper, 14, within the bottle 10, said stopper being spherical and of any proper material, such as porcelain, cork, or metal. An inspection of Fig. 1 will show that when 45 the stopping-ball 14 is not in contact with the

ring 12 said ring does not entirely fill the 50 groove 11, there being quite a space between the lower portion of the face of the ring and the inclined face 2 of the recess 11; but after the bottle has been filled (and it will of course be understood that the class of bottles to which 55 this invention is applicable are designed for use as receptacles for aerated liquids) the pressure of the gas with which the contents of the bottle is charged will act to force the ball 14 upward within the bore of the packing-ring 12, which ring, when so subjected to pressure, will expand at its lower edge and entirely fill the groove 11, the ball passing well up into the bore of the ring, as shown in Fig. 2, so that should the contents of the bottle be unduly cooled, and the pressure thereby decreased, the ring itself will bind upon the stopper and act to hold it in position. It will be noticed from the construction illustrated 60 in the drawings that the recess 11 is depressed 65 at a point about in line with the greatest expansion of the bottle-head, so that, although the defining-walls of the recess are inclined, the glass is not thinner at the lower portion 70 than at the upper portion of the groove or 75 recess.

I am aware that a bottle has been formed with an internal annular groove having its peripheral defining-walls inclined outwardly and adapted to receive a packing having its 80 peripheral face beveled or inclined to correspond with the defining-walls of the groove, and against the under surface of which a ball in the bottle rests when the bottle is filled, and I therefore do not claim such invention. 85 I form the defining-walls of the bore of the ring and the outer peripheral face of the same vertical or parallel to the axis of the bottle, so that when placed in the groove it will not entirely fill the same, thereby permitting it 90 to expand to receive the ball within its bore and hold the same therein, thus preventing all liability of the ball being accidentally displaced and the bottle unstopped.

Having thus fully described my invention, I 95 claim as new and desire to secure by Letters Patent—

The combination, with a bottle provided

with an annular internal groove having outwardly-inclined defining walls, of an elastic apertured packing ring having the defining walls of its bore and its peripheral face vertical or parallel to the axis of the bottle, and a ball within the bottle, substantially as described, whereby provision is made for allow-

ing the packing-ring to expand to receive the ball within its bore and hold the same securely therein, as set forth.

WILLIAM BEARDSLEY.
